Thomas Mackel

UNITED STATES PATENT OFFICE.

THOMAS MACKEL, OF PAWTUCKET, RHODE ISLAND.

FAUCET.

SPECIFICATION forming part of Letters Patent No. 252,046, dated January 10, 1882.

Application filed September 5, 1881. (No model.)

To all whom it may concern:

Be it known that I, THOMAS MACKEL, of Pawtucket, in the county of Providence and State of Rhode Island, have invented certain 5 Improvements in Faucets, of which the following is a specification.

My said invention relates to a faucet for tapping barrels containing fermented liquors; and it consists of a T-shaped cylinder having 10 an elongated and threaded tapering end, and carrying a plunger with which to force the plug or bung from the barrel.

The accompanying drawings are hereby made 15 part of this specification, similar letters of reference thereon indicating corresponding parts.

Figure 1 is a sectional view of the combined parts of the device, showing their operation and mutual relation. Fig. 2 is an external view of said cylinder and of the nut that holds 20 the plunger therein. Fig. 3 of said drawings is a view of the plunger aforementioned.

The outer shell or cylinder (seen in Fig. 2 and at *a a* in the other figures) is cast whole, substantially as shown, and of suitable metal.

25 The tapering and threaded end thereof, (seen at *c*), and also the plunger *d*, are made much longer than similar parts of other faucets now used; and this is an important feature of my device, making it available for tapping any barrel met 30 in the trade, of whatever thickness or form of construction. The end *e* of the plunger is made nearly as large as the interior of the cylinder, and this enlarged end is provided with superficial channels along its sides. This form 35 of construction is adapted in order to prevent the hops or other foreign matter from passing out when the liquors are drawn. When the plunger is placed in the cylinder it is secured therein by means of the nut and packing *ff'*, collar *h*, and shoulder *k*. The collar *h* is made 40 nearly as large as the diameter of the cylinder below the shoulder *k*, in order to prevent leakage when the pressure from within the barrel forces back the plunger and carries the collar against the packing *f'*.

45 The angular attachment to the cylinder (seen at *i*) is intended to take the place of the usual stop-cock heretofore inserted in the cylinder, no stop-cock being necessary in my said device. The object of this part is to provide

means by which to attach to the device the flexible pipe usually used to convey the liquors to their ultimate outlet. If in the absence of the usual stop-cock in the part *i* there should be found to be undue pressure in the 55 connecting pipe, or if for any other reason it may be desired to use the device in the form hereinafter stated, there may be secured to the end *e* of the plunger a guard or valve, made of leather or other suitable material; or the 60 end *e* of said plunger may be cast with a shoulder at the extremity thereof sufficiently large to cover the end *e* of the cylinder when said guard is pressed against it. After the plug shall have been driven in, as hereinafter described, the pressure from within the barrel will 65 force the plunger back again until said guard rests against the cylinder end *c* and tightly enough to prevent the beer from flowing therein. Pressure in any form applied to the end 70 *d* will lift the guard from the cylinder end *c*, and thus permit the beer to flow into and through the faucet as desired.

My said device is used by inserting the tapering end *c* in the hole in the barrel provided for 75 this purpose, the entrance and the incidental displacement of the plug being facilitated by the use of the threaded surface. After the device has been firmly secured in the barrel and the plug or bung has been crowded inward as 80 far as desired, the plug is then driven entirely from the barrel by the application of the requisite force at the opposite end of the plunger, the operation being apparent from the dotted lines and the protruding end of the 85 plunger. (Seen in Fig. 1.) When the bung or plug has been so driven into the barrel the plunger is forced back into place by the pressure from within the barrel, and without the assistance of any spring or other similar device. 90

In case the hole of any barrel may be found to be of extraordinary size, the end *e* of my said device may be temporarily enlarged by screwing thereon a tapering and threaded sleeve.

I am aware that other faucets have been 95 made on a general plan somewhat like that above described; but my invention is directed to a reduction of the number of the parts used, to a simplification of the construction and operation of these parts, and to an adaptation of 100

the device to all barrels of whatever thickness, size of hole, or other peculiarity of construction.

I claim as my invention and desire to secure 5 by Letters Patent—

In a faucet for tapping barrels and other receptacles of fermented liquors, and for drawing the contents thereof, the combination of the cylinder *a a*, made of one piece of metal,

the fluted plunger *d*, having an attached guard *g* to at its end *e*, the nut and packing *ff'*, and collar and shoulder *h k*, all in the manner and for the purposes substantially as described and shown.

THOMAS MACKEL.
